UNITED STATES PATENT OFFICE.

EMMA C. INCE, OF BUFFALO, NEW YORK.

HAMMOCK.

No. 894,008.

Specification of Letters Patent.

Patented July 21, 1908.

Application filed May 13, 1907. Serial No. 373,268.

To all whom it may concern:

Be it known that I, EMMA C. INCE, a citizen of the United States, residing at Buffalo, in the county of Erie and State of New York, have invented a new and useful Improvement 5 in Hammocks, of which the following is a specification.

This invention relates to a hammock designed more particularly as a bed or cradle 10 for infants, but it is also desirable for adults, the same being intended principally for outdoor use on lawns, verandas &c.

The object of my invention is to provide 15 the hammock with an improved hood for protecting the occupant from drafts, inclement weather or strong sunlight.

In the accompanying drawings consisting 20 of 2 sheets: Figure 1 is a perspective view of the hammock, the hood being removed. Fig. 2 is a similar view, with the hood applied. Fig. 3 is a transverse section of the 25 hammock. Fig. 4 is a fragmentary perspective of the same showing the adjacent end of the hood detached and unfolded.

Similar letters of reference indicate corresponding parts throughout the several views.

The body of the hammock may be of any suitable construction but it is preferably of 30 rectangular form and has a flat bottom and comparatively high side and end walls to prevent an infant from falling out of it. In the construction shown in the drawings, the body comprises an upper or top frame consisting of longitudinal side bars A and cross 35 bars A¹ rigidly connected to the ends of the side bars; a similar bottom frame consisting of side bars B and end bars B¹, and open-work material C, such as strong netting, connecting said top and bottom frames and 40 forming the side and end walls of the hammock. The cords of the netting may be looped around the bars of the top and bottom frames as shown, or otherwise attached thereto. To the bottom-frame B, B¹ is secured 45 a padded bottom or mattress B² of any suitable material.

D, D indicate suspension ropes, chains or hangers arranged at opposite ends of the hammock. Each of these ropes is doubled 50 and its branches are secured at their lower ends to the adjacent corners of the top frame, preferably by passing them through holes in the bars A, A¹ of said frame and knotting their ends, as shown. From these 55 bars the branches of each rope converge upwardly for a suitable distance and are united

by a pair of separated knots d, d¹, forming loops e in the two ropes which are adapted to receive a supporting bar or rod F. The latter is provided in opposite edges near its 60 ends with notches f in which the sides of the loops e are seated, confining the bar against longitudinal displacement. At a suitable distance above the knots d¹ the branches of the suspension ropes are again united by 65 knots d² forming loops g, each of which is adapted to engage with a suspension hook h secured to the ceiling or other support.

Combined with each suspension rope D is a spiral spring I which preferably surrounds the 70 same and has end hooks or other suitable attachments i which respectively engage with the upper and lower loops g and e of the cord. The portions d³ of the ropes between the loops e and g are longer than the springs in 75 the normal extended condition of the latter, so that under ordinary conditions said portions remain slack and allow the springs to yieldingly carry the hammock and the occupant and stretch to a safe limit. Should, 80 however, an unusual weight or strain be thrown upon the hammock, the slack portions of the ropes will be drawn taut and the strain exerted upon the ropes alone, thus preventing setting or breakage of the springs 85 and guarding against accidents.

The draft-hood preferably incloses one side, both ends and the top of the hammock and consists of an oblong main portion or section J extending over one side of the hammock from end to end thereof and from its bottom up over the supporting rod F and down to within a few inches of the top frame A, A¹ of the hammock, this last-mentioned portion forming a top flap J¹. The end portions or 95 flaps J² of the hood are of the proper outline and dimensions to extend over the ends of the hammock from side to side thereof and from the bottom frame B, B¹ preferably to within a short distance of the supporting rod 100 F, so as to leave ventilating openings j at their upper ends. Said rod passes through these openings, as shown, and its notches f are in the portions of the rod extending beyond the lateral edges of the top-flap J¹. At 105 their free edges the end flaps J² are provided with suitable fastenings for detachably securing them to the top flap and the ends of the hammock-frames B, B¹, the preferred devices shown in the drawings consisting of 110 complementary interlocking members k, k¹ like those of ordinary glove fasteners.

The draft-hood may be of leather, burlap, canvas, felt or other suitable strong and flexible material which will intercept drafts and exclude light and the weather. While the top, ends and one side of the hammock are thus protected, its other side is left uncovered for ventilation from the bottom of the network C to a few inches above the same. Either or both end-flaps J² of the draft hood or the top-flap J¹ may be folded back when only partial protection is required. Upon detaching said end flaps from the top flap and the hammock-frame, the entire draft-hood can be removed; and if desired, the latter may be replaced in the summer season by a curtain of fine netting or similar open material of substantially the same construction as the draft-hood, to protect the occupant from flies, mosquitos, &c.

Aside from the desirable features above described, the hammock has the advantage of being light and collapsible, enabling it to be easily carried about and compactly stored.

I claim as my invention:

1. In a hammock, the combination of the body having side and end walls, suspension devices for the body, a longitudinal supporting rod arranged above the hammock body and carried by said suspension devices, and a

protecting hood comprising a main portion 30 extending over one side of the body, a top flap extending over said supporting rod, end flaps extending over the end walls of the body and above the same, and means for securing said end flaps to said side flap, substantially as set forth.

2. In a hammock, the combination of the body having side and end walls, suspension devices for the body, a longitudinal supporting rod arranged above the hammock body 40 and carried by said suspension devices, and a protecting hood comprising a main portion extending over one side of the body, a top flap extending over said supporting rod on the inner sides of said suspension devices, and end flaps extending over the end walls of the body and above the same to a point short of said supporting rod, leaving openings between the top-flap and the upper ends of the end-flaps through which said rod passes, substantially as set forth.

Witness my hand this 10th day of May, 1907.

EMMA C. INCE.
